UNITED STATES PATENT OFFICE.

GEORGE E. RIDER, OF KANSAS CITY, MISSOURI.

STEAM-ENGINE.

SPECIFICATION forming part of Letters Patent No. 352,150, dated November 9, 1886.

Application filed November 3, 1884. Serial No. 147,115. (No model.)

To all whom it may concern:

Be it known that I, GEORGE E. RIDER, a citizen of the United States, residing at Kansas City, in the county of Jackson and State of Missouri, have invented certain new and useful Improvements in Steam-Engines; and I do hereby declare that the following is a full, clear, and exact description of the invention, which will enable others skilled in the art to which it appertains to make and use the same, reference being had to the accompanying drawings, forming a part of this specification.

My invention has for its object an improvement in steam-engines in which the steam is admitted in a central relation to and within the cylinder, and to act upon the inner sides of two pistons alternately and exhaust in the space in a central hollow partition arranged between the pistons, in contradistinction to that class of engines having one piston and steam supplied at each end of the cylinder on each side of the piston-head alternately.

My invention consists in the novel means and mechanism for accomplishing the results, hereinafter more fully specified, and pointed out in the claims.

In the drawings, Figure 1 is a view of a steam-engine with the cylinder in longitudinal section, showing the construction and arrangement of the improved parts. Fig. 2 is an end view of the cylinder, showing its flanges and the position of the steam-chest and slide.

A represents the cylinder of the engine. a and a' are the ports leading to the cylinder from the steam-chest. $a' a'$ are flanges on the opposite sections of the cylinder A. $a^2 a^2$ are bolts passing through the flanges $a' a'$ and the partition D. B is the steam-chest. b is the induction-pipe. $b' b'$ are the bolts which pass through the flanges of the steam-chest. C is the slide-valve. c is a groove in the lower part of the slide-valve. $c' c'$ are the nuts on the rod c' and on opposite sides of the slide-valve. c^2 is the rod to slide-valve C. D is the fixed central hollow partition or cylinder-head. $d d$ represent the spaces for the exhaust-steam in partition or cylinder-head D. $d' d'$ are the inclined portions of the partition or cylinder-head D. d^2 is an opening in the partition or cylinder-head D, leading to the spaces $d d$. d^3 is a perforation in the partition D, for piston-rod G. d^4 is a rabbet in the

partition D. E F are the pistons. e is a bolt securing piston E to piston-rod G. H is the induction-pipe. I is the connecting-rod. i is the connecting-bolt.

In the construction of my invention, I make the cylinder A of a single-acting steam-engine in two transverse parts and nearly of equal length. The usual heads to the cylinder on either end I dispense with, and upon those parts of the cylinder which are designed to be united with the central partition or cylinder-head, D, and at their respective ends, I form the flanges $a' a'$, extending laterally and outwardly from said cylinder and as far around its respective part as is necessary to form close joints and permit the steam-chest B to fit directly upon the said cylinder. I then make the partition or cylinder-head D from suitable metal, and in size to extend transversely across and cover each opening in the cylinder presented to said partition or cylinder-head and as far outwardly as will correspond with the extension of the flanges $a' a'$, and in its relative shape. In casting the central partition or cylinder-head, D, I form the same hollow, or with such spaces as is necessary for its purpose around the stuffing-box or perforations for the piston-rod, as seen at $d d$, with close outer walls presented to the openings in the cylinder, and with those parts of said partition or cylinder-head D extending beyond the openings in the cylinder, and of equal width with the flanges, made solid, and the portions d^2 of the partition, which are brought opposite the steam-chest B, inclined toward each other and made narrow, or less than the described thickness of the partition or cylinder-head D at its center. The spaces d , formed in the partition D, are provided with an opening, d' , which communicates with the steam-chest B. The solid portion of the partition D, which extends as far outwardly as the flanges a' , I also make of a reduced thickness, leaving the rabbet a^4 to extend a slight distance within the sides of the cylinder and form a close joint. I then make a central transverse perforation through the partition D, which forms the stuffing-box for the piston-rod and admits the piston-rod G, and of a suitable size, adapted to receive the piston-rod and the packing around said rod. I then place the partition or cylinder-head D between the opposite parts of the cylinder A, provided with the flanges a' ,

and make suitable perforations through said flanges and the solid portions of said partition D, and fasten the respective parts together with the bolts a^2 . When the opposite parts 5 of the cylinder A are thus brought together, the inclinations of the parts d^2 of the partition or cylinder-head D toward each other leave certain spaces between said parts and the end of the cylinder, forming the ports $a a^x$. I then 10 construct a steam-chest, B, of the usual form and with the induction-pipe b entering in at the top of the said steam-chest, and secure the said chest transversely and in a central relation to the outside of the cylinder by the bolts 15 b' , which pass through the flanges on the steam-chest and into the extended portion of the partition D, the said steam-chest thereby covering the ports $a a^x$ in the said cylinder.

A slide-valve, C, is constructed to play in 20 the steam-chest B, over the ports a and a^x , and is made with the transverse groove c in the under side, said groove being formed of the proper depth to admit the steam from one of the ports into the spaces d , made in the central 25 partition or cylinder-head, D, when the valve has cut off the admission of the steam from an opposite port.

Slide-valve C is operated by means of the usual slide-rod, c^2 , which passes through one 30 end of the steam-chest, and is secured to the said slide-valve by the bolts $c' c'$.

Upon piston-rod G, which is attached to the connecting-rod I by means of the connecting-bolt i , and extends through the center of the 35 hollow partition D and within the cylinder, I place the piston F, and in such a manner that said piston F will be rigidly fixed to said rod in proximity to the connecting-rod I, and when in the exhaust-stroke of the piston F said piston 40 is brought near the hollow partition or cylinder-head D, the remaining portion of the piston-rod G will extend to the farthest end of the opposite part of said cylinder, on the opposite side of the said partition or cylinder-head. Upon the same piston-rod G, and which 45 passes through the partition D and within that part of the cylinder upon an opposite side of the said partition or cylinder-head D to that containing the piston F, I place the piston E, 50 and secure the said piston to the end of said rod by the nut e .

In the operation of my invention the steam is admitted through the induction-pipe b to the steam-chest B, and from the said steam-chest 55 to the cylinder A, through the parts $a a^x$, alternately, the slide C cutting off the supply to each port at the proper intervals. The steam, having been admitted through the ports to the cylinder, acts upon the inner sides of the opposite pistons alternately to produce the reciprocating movement of the piston-rod and the rotation of the driving-wheel. When the steam is admitted by the slide through port a 60 to the cylinder, and acting upon the piston E upon its respective side, a communication is 65 formed through port a^x and the groove c with the space d in the hollow partition or

cylinder-head D, and upon the approach of the piston F toward the central partition, D, the exhaust-steam is admitted into the space 70 d in the said partition or cylinder-head through the said port a^x , and conducted from the engine through its eduction-pipe H, which pipe communicates with the hollow partition or cylinder-head D, and has its outlet upon 75 the side of the engine.

The advantages of my invention enable me to obtain a much higher speed with less expenditure of steam and its use expansively, and also to obtain direct action alternately at 80 short intervals upon the pistons without loss of motion or the creation of dead-centers. I also obtain the advantage of being enabled to remove one portion of the cylinder for the purpose of repairs without necessitating the 85 stoppage of the engine, the bolts which pass through the flanges upon the cylinder and also through the central cylinder being placed with the nuts and bolt-heads in alternate order upon opposite sides of the flanges for 90 this purpose.

Having fully described my invention, what I now claim as new, and desire to secure by Letters Patent, is—

1. In a single-acting engine, the combination, with opposite cylinders open at one end, having suitable pistons, of a cylinder-head arranged between said cylinders and provided with a central transverse perforation or stuffing-box adapted to receive the piston-rod, and an annular exhaust-chamber in said cylinder-head around said stuffing-box, for the purpose specified. 95

2. In a single-acting engine, the combination, with opposite cylinders open at one end, 105 of a cylinder-head arranged between said cylinders and the open ends of said opposite cylinders and provided with a central transverse perforation or stuffing-box adapted to receive the piston-rod of pistons on said rod 110 and in said cylinders, and an annular exhaust-chamber in said cylinder-head around said stuffing-box, and ports extending through said cylinder upon opposite sides of said cylinder-head, for the purpose described. 115

3. In a single-acting engine, the combination, with opposite cylinders open at one end, of a cylinder-head or partition arranged between said cylinders and the open ends of 120 said opposite cylinders and provided with a suitable opening or port, a central transverse perforation or stuffing-box adapted to receive the piston-rod of pistons on said rod in said cylinders, and an annular exhaust-chamber in said cylinder-head or partition, and ports 125 extending through said cylinder upon opposite sides of said cylinder-head, a steam-chest, and a slide-valve in said steam-chest adapted to reciprocate over the said ports, as described.

GEORGE E. RIDER.
